DESIGN FOR A BATTERY SELECTOR

Edward C. Tompson, Orange, N. J., assignor to
Thomas A. Edison, Incorporated, West Orange,
N. J., a corporation of New Jersey

Application December 9, 1939, Serial No. 88,792

Term of patent 7 years

To all whom it may concern:

Be it known that I, Edward C. Tompson, a citizen of the United States, residing at Orange, in the county of Essex and State of New Jersey, have invented a new, original, and ornamental Design for a Battery Selector, of which the following is a specification, reference being had to the accompanying drawing, forming a part thereof.

In the drawing:

Fig. 1 is a plan view of a battery selector showing my new design; and

Fig. 2 is an elevational view of the battery selector looking from the top in Fig. 1.

The characteristic features of my design reside in the relative disposition and grouping of the panels or frames, windows and indicial markings substantially as shown.

I claim:

The ornamental design for a battery selector, as shown and described.

EDWARD C. TOMPSOM.
